CLAIM

The ornamental design for a foldable head tent, as shown and described.

DESCRIPTION

FIG. 1 is a front elevational view of a foldable head tent showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view of an unfolded head tent thereof;

FIG. 8 is a rear perspective view of a folded head tent in the folded position;

FIG. 9 is a front perspective view of a foldable head tent used with an unclaimed pillow inside; and,

FIG. 10 is a front perspective view of a foldable head tent in use with an unclaimed human body.

The broken lines of FIG. 9 and FIG. 10 depict environment that forms no part of the claimed design.
